UNITED STATES PATENT OFFICE.

JAMES STAPLETON, OF TODD P. O., PENNSYLVANIA.

IMPROVEMENT IN SNAP-HOOKS.

Specification forming part of Letters Patent No. 222,324, dated December 2, 1879; application filed August 15, 1878.

To all whom it may concern:

Be it known that I, JAMES STAPLETON, of Todd P. O., in the county of Huntingdon, and in the State of Pennsylvania, have invented certain new and useful Improvements in Snap-Hooks; and I do hereby declare that the following is a full, clear, and exact description thereof, reference being had to the accompanying drawings, and to the letters of reference marked thereon, making a part of this specification.

My invention relates to snap-hooks; and it consists in the combination of two half-round bars pivoted together, and having formed therewith loops at one end at right angles to the pivot, and at the other end hooks formed with shoulders, and a double strap having its two parts connected separately to the loops, and provided with a sliding keeper, all as hereinafter more fully set forth.

In order to enable others skilled in the art to which my invention appertains to make and use the same, I will now proceed to describe its construction and operation, referring to the annexed drawings, in which—

Figure 1 is an edge, and Fig. 2 a side, view; while Figs. 3 and 4 are views of the two ends of the snap.

A A represent two metal bars, which are formed alike, each having a hook, B, at one end, and a loop or eye, C, at the other. These bars are made flat on their inner faces, and the two are pivoted together near their loop ends.

Each hook has a shoulder at $x x$, formed by cutting away a portion of the metal. When the hooks are closed together the end of one lies in the recess in the other, so that the two ends are flush with the body.

D represents the leather strap, which is made double at its lower extremity, and each end E thereof is connected separately to one of the loops C.

f represents a sliding keeper, which is brought down close over the two ends of the strap when it is desired to prevent the parts of the snap-hook from being separated. By moving this keeper upward the parts of the hook can be separated very wide, so as to allow a very heavy ring to be passed between the parts, which would not be the case if a single strap passed through both loops.

It will be noticed that the peculiar feature of the invention is the particular form of the hook, having the pivot in the same plane therewith, and having strap-loops in a plane at right angles with said pivot and hooks, so constructed as to receive a strap upon each loop without interfering with the lateral movement to open the hooks.

This construction and relative arrangement admit of the application of two straps or two parts of a bifurcated strap arranged side by side, and so that a keeper holding the straps together also locks the hooks so that they cannot be separated.

Having thus fully described my invention, what I claim as new, and desire to secure by Letters Patent, is—

The hooks B B, pivoted together, with the pivot in the same plane as the hooks, and provided with strap-loops C C, in a plane at right angles with said pivot and hooks, in combination with the separate straps E E and sliding keeper *f*, substantially as and for the purposes herein set forth.

In testimony that I claim the foregoing I have hereunto set my hand this 8th day of July, 1878.

JAMES STAPLETON.
